UNITED STATES PATENT OFFICE.

PEDRO TORELLI, OF BENICIA, CALIFORNIA.

SEWER-TRAP.

SPECIFICATION forming part of Letters Patent No. 242,236, dated May 31, 1881.

Application filed March 26, 1881. (No model.)

To all whom it may concern:

Be it known that I, PEDRO TORELLI, of Benicia, county of Solano, State of California, have invented an Improved Sewer-Trap; and I hereby declare the following to be a full, clear, and exact description thereof.

My invention relates to inlet or slit basins and traps for sewers to be placed at corners of streets and connecting with the sewer-pipes; and it consists in a double compartment chamber, said compartments opening into each other at the bottom, one of which is so constructed as to contain earth or other like substance to prevent the escape of the gas through said compartment, while allowing ready access thereto for purposes of cleaning, the other of said compartments receiving the water and preventing the return and escape of noxious vapors by reason of the separating-partition reaching below the water level. Both compartments are covered by a lid above, and provided with an opening fitted with a plug in the bottom to allow the escape of the water when desired, which remains below the level of the exit-port. These compartments are appropriately provided with inlet and exit ports, the former being in relation with the gutter, the latter connected with the sewer-pipe. A more particular description will hereinafter appear.

The object of my invention is to provide a trap which will prevent the escape of noxious vapors from sewers and from the water remaining in the basin of the trap, and at the same time one which will permit ready access to all its parts for the purpose of cleaning, or for any other necessary reasons.

Referring to the accompanying drawing, the figure is a vertical sectional view of my sewer-trap.

Let A represent the body or casing of the device, preferably made curved or contracted below and flat above. Its upper surface has the large opening B, covered in any appropriate manner by a hinged or removable lid, C, which will allow access to the interior of the casing. This casing A is to be placed in the curb at a corner, and has in its outer wall, facing the gutter, the extended inlet-opening D, and in its inner wall, at a lower level, the exit-opening E, which latter opening connects with the sewer by means of a pipe, which must be

curved back under the casing A to proceed to the main sewer.

The chamber of the casing A is divided into two compartments, *a* and *b*, by the vertical longitudinal diaphragm or partition F extending from the top down nearly to the bottom of the chamber, but being sufficiently raised therefrom to leave a passage between the two compartments. In compartment *b*, just above the level of the exit-opening E, is a horizontal diaphragm, G, dividing the said compartment into two divisions. The diaphragm is provided with an opening, *c*, and fitted with a cover, *d*, which can be easily removed. The space thus formed in compartment *b*, above the horizontal diaphragm G, is filled with some substance, such as earth or sand, or any suitable material which will serve the purpose of preventing the escape of noxious gases from below.

In the bottom of the casing A is the aperture H, closed ordinarily with a plug, connected in any manner (here shown with a chain) with the parts above, whereby said plug may be removed when it is necessary to allow the escape of the water which, being below the level of the exit E, remains in the trap. The aperture H connects with the pipe passing beneath the trap to the sewer.

The operation of the device is as follows: The casing A is placed at the corner in position to receive the water from the gutter at its inlet-opening D. The water then passes down under the vertical diaphragm F, and rises in the compartment *b* until it flows out into the sewer-connection through the exit-opening E. The noxious gases cannot return against the flow of the water, nor can they rise through the compartment *b*, because of the body of earth or sand above it. When either compartment requires to be cleaned easy access is had to them through the lids closing them, as shown, the earth or sand above compartment *b* being taken out and replaced.

When necessary, the plug or stopper in the aperture H may be drawn out, and the water left in the bottom let out into the pipe below connecting with the sewer.

The advantage of my invention is the ease with which it can be reached in all its parts to clean it.

I am aware that sewer-traps have been made

in which a body of water prevents the return and escape of the gas, and that others have been made with more than one compartment. I do not therefore claim, broadly, a sewer-trap made with compartments, nor one in which the inflowing water prevents the return and escape of the gas; but

What I do claim as new, and desire to secure by Letters Patent, is—

- 10 1. A sewer-trap consisting of the casing or shell A, provided with inlet and exit openings D and E, and divided into two compartments, *a* and *b*, by the vertical longitudinal diaphragm F, said compartments being connected with each other below, and the latter compartment being provided with a horizontal diaphragm, G, having an opening, *c*, fitted with a remova-
- 15

ble lid, *d*, the whole device being provided with a removable lid, C, substantially as and for the purpose herein described.

2. A sewer-trap consisting of the casing A, having inlet and exit openings, and divided into two compartments opening into each other below, one of which is provided with a secondary cover, as shown, and the bottom aperture, H, fitted with a removable plug and connected with the sewer, substantially as and for the purpose herein described.

In witness whereof I have hereunto set my hand.

PEDRO TORELLI.
